ATTACHMENT FOR SERVING BOTTLE CAPS
OF VARYING THICKNESSHarry L. Compton, Washington, D. C., assignor
to American Dairy Supply Company, Wash-
ington, D. C.

Application January 7, 1932. Serial No. 585,354

6 Claims. (Cl. 226—92)

This invention relates to attachments for serving or feeding bottle caps of varying thickness to bottle capping machines of the usual construction and operation, employed to close milk bottles for delivery to the users.

Certain types of milk bottle caps in common use have a tab secured upon the upper surface of the disk by means of a staple, the tab being applied to enable the user to pull the disk from the mouth of the bottle. It is found in practice that the tabs and the operation of securing them by staples in the ordinary course of manufacture result in differences of thickness. Furthermore, in the business of capping milk bottles it is often desired and necessary to feed caps that have no stapled tabs thereon, but are plain paper disks. It is the purpose of this invention to enable the disk or other caps to be fed continuously and without interruption to the plunger devices, regardless of the thickness or variation thereof in caps bearing the tabs, and to permit the same attachment to be efficiently operated to feed plain caps. It is not intended to limit this invention to the precise shapes or sizes of the parts set forth.

A preferred form of this invention is illustrated in the accompanying drawing constituting a part of this application.

Fig. 1 of the drawing represents a vertical sectional view through the cap magazine chamber and plunger chamber and the usual support therefor, and shows all parts assembled.

Fig. 2 is a vertical sectional view taken on the broken line 2—2 of Fig. 1 through the divisional wall between the cap magazine chamber and the plunger chamber.

Fig. 3 is a bottom view of the two chambers and the divisional wall. All essential parts of this invention are set out in this view, considered in connection with Fig. 2.

Fig. 4 is a side view of the movable block or gate piece, of which Fig. 5 is an end view, and Fig. 6 a top view.

Throughout the drawing and description the same number is used to refer to the same part.

Considering the drawing, a support 1, which is a common part of a capping machine, carries the cap magazine chamber 2, and a plunger chamber 3 with the usual plunger 4. The caps are served or fed to the plunger upon the guide surface 5 of the supporting member 1.

The chambers have a common divisional wall 6, and formed in the bottom of this wall is a recess 7 usually having the general curved formation as illustrated in Fig. 2. As best shown in

Fig. 1 it will be noted that the recess has a larger lower portion and a smaller upper portion. In the top or upper portion of the recess is a bow spring 8, the ends of which rest against the top of the recess. The spring bears upon the top 60 of a unitary block 10 which movably engages a middle opening in a plate 9 that is secured to the bottom of the wall 6 and closes the recess. The middle opening of the plate is marked 9a in Fig. 2.

The block 10 has a special shape. The form of the bottom is shown in Fig. 3; the shape of the sides in Figs. 2 and 4; the end in Fig. 5 and the narrower top in Fig. 6. In these views it will be observed that the upper portion 11 of block 10 is 70 smaller and narrower than the lower or body portion, and that the block has a projecting shoulder 12. The upper part 11 of the block movable occupies the upper portion of the recess and prevents the block from turning in the recess. 75 As stated, the spring 8 bears upon the upper part 11 of block 10, and the shoulder 12 is introduced to limit the downward movement of the block in the opening 9a of the plate 9.

In the operation of this invention, as the caps 80 are fed from the cap magazine chamber upon the surface 5 which extends beneath the chamber, a simple disk cap without a tab will meet and raise the spring block very slightly, and only a single disk will be permitted to pass to the plunger. If the cap has a tab, it will raise the spring block correspondingly and only one cap will be allowed to pass at a time, and that is the case even if the caps with tabs which follow from the magazine chamber vary slightly in thickness or 90 in which the staples project in differing degrees above or below. It is important that the capping machines may operate continuously without interruption due to spoiled or distorted caps, and it has been found in practice that this invention 95 accomplished the desired object.

Having now described this invention and the manner of its use, I claim:—

1. In an attachment of the character described for bottle capping machines, the combination 100 for a support, of a cap magazine chamber, a plunger chamber, a plunger adapted to reciprocate therein, a recess in the bottom of the wall of the plunger chamber, a plate secured to the wall to cover the recess and having an opening, 105 a block having a portion movably occupying said opening, the said block having shoulders arranged to limit the downward movement of the block in the opening, and a spring in the recess 110 above the block.

2. In an attachment of the character described for bottle capping machines, the combination with a support, of a cap magazine chamber, a plunger chamber, a plunger adapted to reciprocate therein, a recess in the wall bottom of the plunger chamber, a plate secured to the wall and having an opening, a block having a portion movably occupying the said opening, and a bow spring in the recess above the block having its middle portion bearing downwardly upon the block and its end portions in contact with the top of the said recess of the plunger chamber wall. 80
- 10 3. In an attachment of the character described for bottle capping machines, a plunger chamber and a cap magazine chamber having a division wall between them, a recess formed in the bottom of said wall, a plate secured to the wall bottom to cover the recess and having an opening in the middle, a block having a portion movably occupying the said opening, means for limiting the downward movement of the block, and a spring arranged between the top of the recess and the top of the block. 85
- 15 4. In an attachment of the character described for bottle capping machines, a plunger chamber and a cap magazine chamber having a division wall between them, a recess formed in the bottom of said wall, a plate secured to the wall bottom to cover the recess and having an opening in the middle, a block having a portion movably occupying the said opening, said block having a shoulder arranged to limit the downward movement of the block, and a spring arranged between the top of the recess and the top of the block. 90
- 20 35 5. In an attachment of the character described for bottle capping machines, a plunger chamber and a cap magazine chamber having a division wall between them, a recess formed in the bottom of said wall to cover the recess and having an opening, a unitary block having a larger lower portion and a smaller upper portion, a plate secured to the bottom of said wall to cover the recess and having an opening, a unitary block having a larger lower portion and a smaller upper portion adapted to occupy the said recess movably, and a spring in the said smaller portion of the wall recess above the block, the said larger portion of the block engaging the opening in the plate. 95
6. In an attachment of the character described for bottle capping machines the combination with a plunger chamber and a cap magazine chamber having a division wall between them, the said wall having a recess formed in the bottom thereof and having a larger lower portion and a smaller upper portion, of a plate secured to the bottom of said wall to cover the recess and having a middle opening, a unitary block having a larger lower portion and a smaller upper portion adapted to occupy the said recess movably, the said block having a shoulder disposed to limit the movement of the block downwardly in said opening, and a spring in said smaller portion of the recess above the block, the said larger portion of the block engaging the opening in the plate. 100
